UNITED STATES PATENT OFFICE

ARTHUR PRITCHARD AND CHARLES MONKS, OF LONDON, ENGLAND

MANUFACTURE OF TENNIS AND OTHER RACKETS

Application filed November 7, 1929, Serial No. 405,443, and in Great Britain September 6, 1929.

This invention relates particularly to the drilling of the string holes in the frames of tennis and other rackets.

According to common practice the positions of these holes are marked off on the frames of the rackets by hand the drilling of the holes thus marked off being similarly effected. These operations, therefore, call for a certain amount of skill and however 10 carefully they are effected it is almost impossible to drill all the holes with equal accuracy.

The object of the present invention is to provide a machine which will effect both operations mechanically and with repeated accuracy.

Broadly the invention consists of an apparatus for drilling the string holes in the frames of tennis and other rackets comprising a drill of fixed location, means for supporting each frame relative to the drill to ensure predetermined lateral spacing of the drilled holes from the sides of the frame and means for controlling the movement of 20 the frame from one drilling position to another drilling position to ensure predetermined longitudinal spacing of the holes from each other around the frame.

In order that the invention may be clearly 30 understood and carried into effect two embodiments of the same will now be described by aid of the accompanying drawings in which:—

Fig. 1 is a side elevation of a machine constituting part of the apparatus according to one embodiment of the invention.

Fig. 2 is a plan view of the same machine.

Fig. 3 is a plan view of the frame constituting the other part of the apparatus according to the same embodiment of the invention.

Fig. 4 is a section through the same on the line 4—4 of Fig. 3.

Fig. 5 is a plan view of a revoluble head constituting an alternative means for controlling the movement of the frame from one drilling position to another drilling position to ensure predetermined longitudinal spacing of the holes from each other around the frame.

Fig. 6 is a vertical section through such head.

Fig. 7 is a side elevation view showing the same when mounted in position on its supporting table.

Fig. 8 is a top plan view of such supporting table with the head removed.

In general an apparatus according to this invention comprises a suitable frame 1 which supports a drill head 2 which carries in bearings a horizontal spindle 3 on the outer end of which is mounted a suitable drill chuck 4 for the reception of the required drill which is denoted in Fig. 1 by the reference numeral 5. The outer end of this drill is supported by a guide formed in an adjustably mounted bracket 6. The spindle 3, which in the example illustrated is driven by an electric motor 7 through the medium of a belt 8 and fast and loose pulleys 9, is free to move axially, this movement in a forward direction being imparted by a foot pedal 10 through the medium of a flexible connection 11 and against a spring 12 and the return movement being imparted by such spring. This spring therefore maintains the spindle and the drill carried thereby in the normal or retracted position.

An inclined table 13 is provided for supporting the work to be drilled. This table is in turn supported by the frame of the machine in such a manner that it may be angularly adjusted according to the required angle of the holes to be drilled. This is effected in the example illustrated by means of the independently adjustable front and rear supports 14 and 15 respectively. This table in conjunction with the jig 16 illustrated in Fig. 3 constitute one suitable means for supporting each frame to be drilled relative to the drill to effect lateral spacing of the drilled holes from the sides of the frame.

The jig illustrated is composed of metal, is of skeleton formation and is of such a depth and shape as to be capable of receiving between its flat sides 17, the frame to be drilled. To permit of the insertion of a frame one half of the jig is composed of two sections 18 each of which is hinged to the adjoining part of the jig as at 19. When the two sections are 100

closed about a positioned frame they are held together by means of suitable catches 20. The frame is centered in the jig by means of screw clamps the jaws 21 of which are opened and closed about the positioned frame by means of set screws 22. The inside edge of each flat surface of the jig is formed with notches 23 corresponding to the positions of the holes to be drilled in the frame. To facilitate the drilling of each hole at the required angle the flat surfaces of the jig may, as illustrated, be marked off with lines 23^a opposite each notch 23 and in operation these lines are intended to be brought successively into aligned registration with a further line of marking, 6^a on a finger 24.

The means illustrated in Fig. 1 for controlling the movement of the jig and its contained frame from one drilling position to another drilling position comprises a spring pressed finger 24, see Fig. 1, mounted upon the bracket 6 and above the drill beyond which it extends forwardly for a predetermined distance. This finger is adapted to be engaged in each of the notches 23 in turn.

In operation the jig with a positioned frame is placed upon the upper surface of the inclined table 13 so as to encircle the drill. The jig is then moved to cause the spring pressed finger 24 to engage in one of the aforesaid notches 23 when the jig is forced towards the drill, against the action of the spring pressed finger, which moves with it, until the inside face of the racket frame comes against a fixed stop 25 in which position it is held until the required hole has been drilled. The markings on the jig and the drill head finger 24 are then brought into alignment after which the drill is fed forward by the operation of the foot pedal 10, to effect the drilling of the hole. The pedal is then released and the drill is automatically withdrawn to its normal position again by the action of the spring 12. The operation is then repeated until one series of holes has been drilled. The jig is then turned completely over onto its opposite face and the second series of holes is similarly drilled.

Another suitable means for controlling the movement of the frame from one drilling position to another drilling position to effect predetermined longitudinal spacing of the holes from each other around the frame is illustrated in Figs. 5 to 8 and comprises a circular member or head 26 which is mounted to be freely rotatable about a pivot 27 which pivot is carried by a supporting platform 28 upon which the base of the circular member or head rests. This supporting platform is arranged at an angle to the axis of the drill and above the same so as to support the aforesaid head at a similar angle. Projecting at intervals from and around the periphery of this head are a plurality of pins 29 the outer extremities of which are pointed or otherwise

sharpened. These pins are spaced at varying distances from each other for a purpose hereafter to be described and are so mounted in bearings in the head as to be capable of longitudinal movement. The outward movement of the pins is resisted by coil springs 30 encircling the inner end of each pin and such outward movement is imparted to all of the pins simultaneously as and when required by a conical member 31 which is mounted upon a threaded stem 32 projecting vertically and centrally from the upper surface of the aforesaid head. By rotating this conical member in either direction the same is caused to move up and down the threaded stem and to thus vary the distance the pins project outwards from the periphery of the head. A lock-nut 32^a is provided for locking this member in the adjusted positions.

In operation the jig with a positioned frame is placed upon the upper surface of the inclined table 13 so as to encircle the drill. A centre mark previously placed on the interior surface of the frame at the narrow or handle end thereof is then brought into registration with a corresponding mark on the head. The frame is then pushed towards the drill point into engagement with a stop 33 against which it is held during each drilling operation. This movement of the frame causes the middle or nearest pin on the head to engage the wood of the frame at a point just above the drill. The drill is then fed forward until the hole is drilled through the frame. The pedal or other device is then released and the drill is automatically withdrawn to its normal position again by the action of the spring 12. The frame is then turned whilst still held against the aforesaid stop 33 until the next pin on the head is brought into alignment with the point of the drill. This movement of the head is effected by the continued engagement of the first pin with the racket frame and such engagement continues until the next following pin has engaged the frame and is in alignment with the drill. The drilling operation is then repeated and is continued until one series of holes has been drilled around the frame. The next series of holes, which alternate with the holes of the first series but which are in a different plane from the first series, are drilled as described in connection with the first embodiment by turning the jig and its contained frame completely over on the inclined table so that the opposite side of the jig rests upon such table.

As the spacing of the holes around the frame varies from a minimum at the lower or handle end of the frame to a maximum at the opposite end of the frame the pins on the revolvable head are correspondingly spaced. A different head may be provided for each different spacing of the holes.

By varying the distance the pins project

from the head by the means aforementioned the effective diameter of the head is correspondingly varied thus permitting the one head to be used for rackets having different internal measurements.

It will, of course, be understood that the invention contemplates the use of any suitable means for supporting the frame relative to the drill for the purpose of ensuring predetermined lateral spacing of the drilled holes from the sides of the frame and any suitable means for controlling the movement of the frame from one drilling position to another drilling position. The movement of the frame from one drilling position to another drilling position may also be effected mechanically instead of by hand as just described.

Further, the aforesaid revolvable head may be used for marking-off purposes independently of the other devices, the holes being then drilled in any known manner.

What we claim is:-

1. Apparatus for drilling the string holes in the frame of tennis rackets and the like comprising, in combination, an adjustable supporting table adapted to be tilted to any desired angle, a horizontally disposed longitudinally movable drill spindle extending thru said table when inclined, a jig frame adapted to support a racket frame about the drill head whereby the holes may be drilled at an angle, and means on said table and cooperating with said frame adapted to facilitate predetermined longitudinal spacing of the drilled holes thru the sides of the frame.

2. Apparatus for drilling the string holes in the frame of tennis rackets and the like comprising, in combination, an adjustable supporting table adapted to be tilted to any desired angle, a horizontally disposed longitudinally movable drill spindle extending thru said table when inclined, a jig frame adapted to support a racket frame about the drill head whereby the holes may be drilled at an angle, and means on said table and cooperating with said frame adapted to facilitate predetermined longitudinal spacing of the drilled holes thru the sides of the frame, said means including a resilient member adapted to coact with said jig frame.

3. Apparatus for drilling the string holes in the frame of tennis rackets and the like comprising, in combination, an adjustable supporting table adapted to be tilted to any desired angle, a horizontally disposed longitudinally movable drill spindle extending thru said table when inclined, a jig frame adapted to support a racket frame about the drill head whereby the holes may be drilled at an angle, and means on said table and cooperating with said frame adapted to facilitate predetermined longitudinal spacing of the drilled holes thru the sides of the

frame, said jig frame having notches and a spring pressed finger adjacent the drill adapted to coact with said notches in the jig frame thereby positively to determine the drilling of the holes in predetermined spaced relation.

4. Apparatus for drilling the string holes in the frame of tennis rackets and the like comprising, in combination, a supporting table, a longitudinally moving drill spindle, means for supporting the racket frame about the drill head and on the supporting table so as to facilitate predetermined lateral spacing of the holes to be drilled from the racket sides, and means cooperating with said racket supporting means adapted to facilitate predetermined longitudinal spacing of the holes to be drilled through the sides of the frame.

5. Apparatus for drilling the string holes in the frame of tennis rackets and the like comprising, in combination, a supporting table, a longitudinally moving drill spindle, a jig frame adapted to support a racket frame about the drill head and on the supporting table so as to facilitate predetermined lateral spacing of the holes to be drilled from the racket sides, and means cooperating with further means on the jig frame adapted to facilitate predetermined longitudinal spacing of the holes to be drilled through the sides of the frame.

In testimony whereof we affix our signatures.

ARTHUR PRITCHARD.
CHARLES MONKS.
